STOCKING

Paul R. Nestler, Sr., Walnut St., Green Lane, Pa.

Filed Mar. 17, 1966, Ser. No. 1,514

Term of patent 14 years

(Cl. D47—7)

The figure is a side elevational view of a stocking showing my new design, the side opposite being a mirror image thereof.

The undisclosed side of the stocking is the same as that disclosed.

I claim:

The ornamental design for a stocking, as shown and described.
